UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

ELECTRIC AIR-HEATER.

1,396,813.

Specification of Letters Patent.

Patented Nov. 15, 1921.

Application filed April 4, 1919. Serial No. 287,576.

To all whom it may concern:

Be it known that I, ORA A. COLBY, a citizen of the United States, and a resident of Irwin, in the county of Allegheny and 5 State of Pennsylvania, have invented a new and useful Improvement in Electric Air-Heaters, of which the following is a specification.

My invention relates to electric heating 10 and particularly to electric air heaters.

One object of my invention is to provide an electric air heater of simple and rugged 15 design in which the heater units are composed of rods of solid conducting material.

Another object of my invention is to provide an electric air heater using solid carbonaceous material that has a negative temperature-resistance coefficient, for the resistance units, so arranged that no external current-regulating means will be required.

The resistance materials usually employed in electric heaters have a positive temperature-resistance coefficient, and are, therefore, self-regulating in regard to the amount of 20 current traversing the resistor. When carbonaceous material, which has a negative-temperature-resistance coefficient, is used, the resistance of the material tends to decrease as its temperature increases until it may become incandescent and lose its original self-sustaining form. I have found that, by 25 properly proportioning the resistance units and by providing additional radiating surface therefor, it is possible to use carbonaceous material for resistors and to operate 30 the same at a reasonably low temperature that will permit of using such heaters in ordinary rooms.

In practising my invention, I provide a 35 suitable metal frame for supporting a number of rods of solid carbonaceous material which may be traversed by the current and be heated thereby. These rods have a greater cross sectional area in the end portions 40 that in the body portions, so that the end portions will have a less energy loss than the body portions and will, therefore, operate at a lower temperature. I provide suitable clamping members which serve as connectors and also help radiate the heat from 45 the end portions of the resistance rods.

In the single drawing, Figure 1 is a front view of an air heater embodying my invention, and Fig. 2 is an end view thereof.

Fig. 3 is a side elevation of a plurality of 55 resistance rods of one type embodying my invention combined with connecting clamps and supporting means, certain parts being cut away to show details of construction; and Fig. 4 is an end elevation of the same 60 apparatus. Fig. 5 is a side elevation of a modification of the device embodying my invention, using clamping and connecting members at the top, as well as at the bottom, of the rods; Fig. 6 is an end elevation there- 65 of, and Fig. 7 is a plan view of the structure shown in Figs. 5 and 6, certain parts being cut away to show more clearly certain details of construction.

Referring to Figs. 1 and 2, a heater 10 comprises metal end frames 11 and an intermediate cover portion 12 made of pressed sheet steel, cast iron, or similar suitable material, the three parts being suitably secured together. Suitable terminals 13, insulated 70 from one end member 11, are provided to enable connection to be made to an electric supply circuit.

Referring to Figs. 3 and 4, a suitably formed supporting bar 14 is provided with 80 holes 15 in the end portions to enable it to be secured, by means of bolts, (not shown) to the end frames 11. Two end members 16 and a plurality of intermediate members 17 are attached to the supporting bar 14 by 85 means of screws 18, a plate 19, of insulating material, being placed between the members 16 and 17 and the bar 14, and a washer 20, of insulating material, being placed between the head of each screw 18 and the bar 90 14. The members 16 and 17 serve as conductors of current and also assist in radiating the heat in a manner to be more fully described hereinafter. The end members 16 are adapted for attachment to current con- 95 ductors (not shown), screws 21 being provided to clamp the ends of the conductors in holes 22 drilled in said end members, the other ends of the current conductors being connected to the terminals 13. Each of the 100 intermediate members 17 is provided with two holes 23 and the end members 16 with one such hole to receive the ends of resistance rods 24 of substantially U-shape. The end portions of the rods 24 may be of any 105 desired form, in cross section, they being here shown as of circular cross section. The body portion is, preferably, of substantially

rectangular or oval cross section and of lesser area than the end portions, the object being to obtain a lower resistance in the end portions than in the body portions and, consequently, to generate only a small amount of heat in the end portions, thus reducing the operating temperature of these portions. The holes 23 are larger than the rods 24, so as to provide a space in which may be placed a mass 25, of finely divided granular-conducting material, such as graphite. A washer 26 is provided to cover the hole 23 and the granular material 25 therein.

Figs. 5, 6 and 7 show another embodiment 15 of my invention, using straight resistance rods and suitable clamping members at both ends of the rods. Supporting bars 14 are provided at the top and the bottom of a plurality of straight resistance rods 27. A 20 two-part clamping member 28 of copper, brass, or other similar metal, is provided at the lower end of each of the end rods 27 and is fastened to the bar 14 by means of screws 18, being insulated therefrom by plates 19 of insulating material, placed at each side of the bar 14. A bolt 29 securely clamps the rods 27 in the two-part clamping members 28, substantially semi-cylindrical recesses 30 being provided in said members to receive 25 the rods 27. Similar two-part clamping members 28 are provided for the intermediate rods 27, each part having two semi-cylindrical recesses 30 to receive a corresponding number of rods. The clamping 30 members are so disposed at the top and the bottom of the resistance rods as to connect all of the rods in series, although the clamping members may be arranged to connect a plurality of rods in parallel if the resistance 35 of the rods should make this necessary or desirable. The end clamping members are provided with holes and binding screws, as described for the end members 16 in Fig. 3.

The rods 27 are made of solid carbonaceous material and have end portions that are larger in cross section than the body portion in order to reduce the heat generated in the end portions. The clamping members 28 are made relatively large so as to assist 40 in radiating the heat from the end portions of the resistance rods and thus keep the operating temperature relatively low, as compared with the temperature of the body portions. The decrease of the resistance of 45 carbonaceous material at increased temperatures will be counter-acted by the increased radiation of the clamping members, as they conduct heat away from the end portions of the rods and radiate the same. By these 50 means, the maximum temperature of the resistance rods may be kept within a limit that will allow of long continued use of the same without deterioration of the material, and the temperature of the resistance rods

will be such as will adapt a heater of this 65 type to be used as an air heater or as an electric fireplace in living rooms.

While I have shown a specific embodiment 70 of my invention, various changes may be made therein without departing from the spirit and scope of my invention, and I desire that only such limitations shall be placed thereon, as are imposed by the prior art or are specifically set forth in the appended claims.

75 I claim as my invention:

1. A resistance unit composed of solid conducting material having an initially negative temperature-resistance coefficient and comprising a bare body portion and integral end portions, the body portion having a higher resistance and a smaller radiating surface per unit of length than the integral end portions thereof whereby a constant resistance of said body portion is maintained at a predetermined temperature.

2. In a resistance unit of solid conducting material having an initially negative temperature-resistance coefficient, the combination with a bare body portion and integral end portions, the body portion having a higher resistance and a smaller radiating surface per unit of length than the end portions, whereby the resistance of said body portion becomes constant at a predetermined 95 temperature and means for conducting the heat away from said end portions and radiating the same.

3. An electrical heating device comprising 100 a frame, a plurality of contact members having openings therein, means for supporting said contact members in spaced relation in said frame, a resistance unit of solid carbonaceous material having a negative temperature-resistance coefficient and having its 105 ends located in the openings in said contact members, and a mass of granular electrical-conducting material in said openings interposed between said contact member and said resistance unit.

4. An electrical heating device comprising 110 an open frame, a plurality of metal contact members having openings therein, means for supporting said contact members in spaced relation in said frame, a resistance unit of solid carbonaceous material of substantially U-shape, having a negative temperature-resistance coefficient, and having its ends located in the openings in said contact members, a mass of granular electrical- 115 conducting material in said openings interposed between said contact member and the end portion of said resistance unit, and a cover member for said openings.

120 In testimony whereof I have hereunto 125 subscribed my name this 22nd day of March, 1919.

ORA A. COLBY.
